UNITED STATES PATENT OFFICE.

LEO K. STAFFORD, OF DETROIT, MICHIGAN, ASSIGNOR TO THE STAFFORD ROLLER-BEARING CAR TRUCK CORPORATION, OF CARLSTADT, NEW JERSEY, A CORPORATION OF NEW JERSEY.

ROLLER-BEARING FOR RAILWAY-TRUCKS.

1,374,775.

Specification of Letters Patent. Patented Apr. 12, 1921.

Application filed September 6, 1919. Serial No. 322,027.

To all whom it may concern:

Be it known that I, LEO K. STAFFORD, a citizen of the United States, residing at Detroit, in the county of Wayne and State 5 of Michigan, have invented new and useful Improvements in Roller-Bearings for Railway-Trucks, of which the following is a specification.

This invention has reference to an improvement in truck construction for rolling stock.

The primary object of the invention is to provide the bearing box of a railway truck with anti-frictional means between the box 15 and the spindle or journal of the axle to insure the free turning of the wheel under all conditions.

A further object of the invention is to provide a journal box for trucks of the 20 standard construction with anti-frictional rollers arranged in a suitable cage and properly spaced and retained from contact with each other, and to provide the journal or spindle of the car axle with a 25 case hardened sleeve on which the rollers bear.

A further object of the invention is to arrange between the journal box of a standard truck for rolling stock anti-frictional rollers which are positively held against longitudinal movement, said rollers bearing on 30 case hardened elements, one of which surrounding and being secured to the journal or spindle of the axle and the other being 35 wedged or otherwise secured on the journal box, in addition to the provision of means whereby a lubricant may be fed to the roller bearing.

It is a further object of the invention 40 to provide anti-frictional means between the journal box of a truck and the spindle or journal of a car wheel axle which may be applied without alterations to standard trucks and standard axles.

It is a still further object of the invention 45 to provide means for reducing the friction between the journal boxes of trucks and the journals or spindles of axles received in said boxes which shall be of a 50 simple and comparatively cheap construction and which will perform the functions for which it is devised with accuracy, certainty and without danger of wear or other

injury to either the axles or bearing or journal boxes.

Other objects and advantages will present themselves as the nature of the invention is more fully disclosed, reference being had to the accompanying drawings in which there is exemplified a simple and satisfactory reduction of the improvement to practice, it being understood, however, that the nature of the invention is such as to render the same susceptible to various modifications, all of which falling within the scope 65 of what is claimed.

In the drawings:

Figure 1 is a top plan view of the boxing at one end of an ordinary or standard car truck illustrating certain features of my 70 improvement.

Fig. 2 is a sectional view approximately on the line 2—2 of Fig. 1.

Fig. 3 is a sectional view approximately 75 on the line 3—3 of Fig. 1.

Fig. 4 is a sectional view approximately on the line 4—4 of Fig. 3.

Fig. 5 is a detail fragmentary perspective view of one of the ring members that forms 80 one end of the cage for the anti-frictional rollers.

Fig. 6 is a detail perspective view looking 85 toward one end of one of the anti-frictional rollers.

As is well known to those skilled in the art, the axles for the wheels of rolling stock as well as the boxes on the ends of the trucks which receive the spindles or journals of the said axles, are constructed of cast steel 90 and are not tempered. This is necessary because a slight but determined amount of yieldability is required between the axles and bosses and were either of these elements tempered the same would be rendered non-yieldable and consequently liable to break- 95 age.

In carrying out my invention I make use of the standard trucks 7 that have their ends integrally formed with the boxes 8, the bores of the said boxes being round, and the said bore being indicated in the drawings by the numeral 9. In the bore 9 I arrange a case hardened tube 10. Preferably I provide the tube, on its outer periphery with a longitudinally extending rib 11 designed to enter a longitudinal groove 12

which I form in the bore of the boxing. However, it is to be understood that the case hardened steel tube 10 may be secured in the bore in other manners, it being, however, necessary to retain the tube against both longitudinal and turning movement in the bore.

On the outer end of the boxing 9 there is arranged a grease chamber 13 that has a ported communication 14 with the bore of the boxing, and the tube 10 is provided with a number of openings that aline with the ports 14. The grease or lubricant chamber 13 has arranged therein a follower plate 15, the same having a centrally arranged stem 16 that passes through the removable top 17 of the chamber 13. The top is preferably secured to the chamber by wing nuts 18, but other securing means may be employed. Surrounding the stem 16, and exerting a pressure between the top 17 of the chamber 13 and the upper wall of the follower plate 15 is a spring 19. The stem 16 is in the nature of an indicator, and the spring 19 is of a strength to force the follower plate 15 the entire depth of the chamber 13. It will thus be apparent that as the grease between the plate 15 and the lower wall of the chamber 13 is used up the stem 16 will be moved inwardly (although not entirely) in the chamber 13 so that the amount of grease in the chamber is thus readily determined.

The numeral 20 indicates a car or engine axle which has its ends reduced in the usual manner to provide spindles or journals indicated by the numeral 21. The spindle 21, in the present instance is surrounded by a case hardened steel sleeve 22, the inner end 40 of the said sleeve being slightly flared as at 23 at its point of contact with the shoulder between the axle and the spindle therefor. The sleeve has its outer end flanged inwardly as at 24 and has its inner wall provided with 45 a longitudinally extending rib or key 25 that is received in a longitudinally arranged groove 26 in the spindle 21.

The anti-frictional rollers, which I employ, are indicated by the numerals 27. 50 Each of these rollers has its ends provided with preferably conical depressions 28. The housing for the rollers comprises end annular members or rings 29 and 30 respectively. These rings, upon their confronting faces 55 and at suitable spaced intervals are provided with inwardly extending substantially cone-shaped tips 30' that are designed to be received in the conical depressions 28 of the rollers, and consequently provide stub shafts 31 or trunnions for the said rollers. Between the rollers the end members of the cage are connected by longitudinally extending bars 31 that may have their ends riveted, bolted or otherwise connected to the said end members. The cage rollers are designed to be

passed through the entrance opening to the boxing to bring the same in engagement with the case hardened tube 10 and with the case hardened sleeve 22. The cage rollers are limited in their inward movement by 70 contact of the member 30 of the said cage with the flared end 23 of the sleeve 22 and are held against outward longitudinal movement by a stop plate 32. The plate 32 has its lower edge concaved or rounded inwardly 75 as at 33 so that the same is arranged above the plane of the sleeve 22, and the said plate has its upper edge formed with a widened head 34 that rests on the top of the boxing 8, the plate proper passing through an opening 80 35 in the top of the said boxing. On the boxing to the opposite sides of the head 34, and adjacent to the ends of the said head there are formed pairs of upstanding ears 36 and 37 respectively. The head 34 is 85 snugly received between the pairs of ears so that the opening 35 is fully closed and entrance of dust or foreign matter to the bore of the boxing is thus prevented. The head 34 of the plate 32 is pivoted, as at 38 between 90 the ears 36 and is provided with an opening 39 that alines with registering openings in the ears 37. Through these openings pass a suitable fastening element in the nature of a cotter pin or the like which is indicated 95 by the numeral 40. The edge of the plate 32 nearest the latching means 40 is rounded inwardly and downwardly as at 41 so that when the latching means 40 is removed the plate 32 may be swung outwardly, and when 100 the door 43 of the boxing 8 is swung to open position the cage bearing may be readily removed after the boxing has been jacked up. A hooked rod or similar implement may be utilized as the means for removing the cage, 105 the same engaging with the outer end member of the cage for the rollers, and between a pair of said rollers facilitating such removal.

It is thought from the foregoing description, when taken in connection with the drawings that the simplicity and advantages of my improvement will be understood and appreciated it being noted that the rollers are constantly lubricated by the grease from 110 the grease chamber 13, that the case hardened steel bearing members prevent injury to either the boxing or the axle, and that the caged rollers may be easily and quickly applied between the axle and the boxing 115 and as readily removed therefrom should occasion require. It is to be further noted that should any frictional engagement occur between the outer end member of the cage and the stop plate 32, such engagement would 120 have a tendency to hold the plate in its closed position.

Having thus described the invention, what is claimed as new, is:—

1. In combination with the boxing of the 130

truck of a rolling stock having a round bore provided with a longitudinal groove, of a case hardened steel tube received in the bore, a longitudinal rib on said tube received in said groove, said boxing designed to receive the spindle end of an axle, said spindle having a longitudinal groove, a case hardened steel sleeve having its outer end flanged and provided with an inner longitudinal rib arranged over the spindle and the said rib being received in the groove of the spindle, caged anti-frictional rollers received in the bore, surrounding the spindle and finding a bearing between the sleeve and groove, means for holding the cage against longitudinal movement in both directions, and the means for holding the cage against outward movement being removable.

2. In combination with the boxing of a truck for rolling stock having a circular bore and a hinged door closing the outer end

thereof, said bore having a longitudinal groove, a case hardened steel tube received in the bore, a longitudinal rib on said tube received in the groove, said bore designed to receive the spindle end of an axle, a case hardened steel sleeve having its outer end flanged inwardly arranged on the spindle and removably secured thereto, rollers in the groove finding a bearing on the sleeve and tube, said rollers having their ends depressed, a cage comprising end ring members having seats received in the said depressions, connecting rods between the ring, the inner ring having a slight contacting engagement with the inner end of the sleeve, and a pivoted stop plate carried by the boxing and disposed opposite the outer ring of the cage to hold the said cage against outward longitudinal movement.

In testimony whereof I affix my signature.
LEO K. STAFFORD.
